DESIGN FOR A CHAIR

Gilbert Rohde, New York, N. Y.

Application February 9, 1940, Serial No. 90,158

Term of patent 3½ years

To all whom it may concern:

Be it known that I, Gilbert Rohde, a citizen of the United States of America and resident of the city of New York, county of New York, and State of New York, have invented a new, original, and ornamental Design for a Chair, of which the following is a specification, reference being had to the accompanying drawing, forming part thereof.

In the drawing:

Figure 1 is a front elevational view of a chair showing my new design.

Figure 2 is a side elevational view of the chair shown in Figure 1.

Figure 3 is a front perspective view of the chair shown in Figure 1.

Figure 4 is a rear perspective view of the chair shown in Figure 1.

Figure 5 is an enlarged detail sectional view showing one of the chair legs as seen from the plane 5—5 on Figure 1.

The characteristic features of my design reside in the portions shown in solid lines.

I claim:

The ornamental design for a chair, as shown and described.

GILBERT ROHDE.
